UNITED STATES PATENT OFFICE

HENRY L. LANGKNECHT, JR., OF ROCHESTER, NEW YORK, ASSIGNOR TO SHURON OPTICAL COMPANY, INC., OF GENEVA, NEW YORK, A CORPORATION OF NEW YORK

DESIGN FOR A METALLIC PATTERN STRIP FOR SPECTACLE FRAMES OR SIMILAR ARTICLES

Application filed May 6, 1931. Serial No. 39,734. Term of patent 14 years.

To all whom it may concern:

Be it known that I, HENRY L. LANGKNECHT, a citizen of the United States of America, residing at Rochester, in the county of Monroe, State of New York, have invented a new, original, and ornamental Design for a Metallic Pattern Strip for Spectacle Frames or Similar Articles, of which the following is a specification, reference being had to the accompanying drawings, forming part thereof.

Figure 1 is a side elevation of a segment of a metallic pattern strip for spectacle frames or similar articles showing my new design.

Figure 2 is an inverted plan view of the same.

Figure 3 is a transverse sectional view taken on line 3—3, Figure 2.

The article of this invention consists in a metallic pattern strip for forming spectacle and eyeglass frames, including eye wires, temples, bridges and the like, having a surface ornamentation applied thereto which is of the appearance of a beaten or hammered surface.

I claim:

The ornamental design for a metallic pattern strip for spectacle frames or similar articles substantially as shown and described.

HENRY L. LANGKNECHT.
